Patented Oct. 11, 1955

175,815

PORTABLE AUTOMOBILE SERVICE STATION OR SIMILAR ARTICLE

Thomas E. Wideman, Sweetwater, Tex.

Application June 20, 1955, Serial No. 36,607

Term of patent 14 years

(Cl. D13—1)

Fig. 1

Fig. 2

Fig. 3

Fig. 4

Fig. 5

Figure 1 is a top plan view of a portable automobile service station showing my new design.

Figure 2 is a front elevational view.

Figure 3 is a rear elevational view.

Figure 4 is an end elevational view, and

Figure 5 is an elevational view of the opposite end of said portable automobile service station.

I claim:

The ornamental design for a portable automobile service station or similar article, substantially as shown.
